(57) **CLAIM**

The ornamental design for a dual-component cremation urn structure, as shown and described.

DESCRIPTION

FIG. 1 is a top, front perspective view showing our new, original design of a dual-component cremation urn structure comprised of two identically shaped, cooperatively engaged cremation urns;

FIG. 2 is a top, rear perspective view thereof;

FIG. 3 is a top, left side perspective view thereof;

FIG. 4 is top, right side perspective view thereof;

FIG. 5 is a top plan view thereof, the bottom plan view being identical thereto;

FIG. 6 is a top plan view of one of the individual cremation urns shown separately for purposes of illustration;

FIG. 7 is a bottom plan view of one of the individual cremation urns shown separately for purposes of illustration, the opposite side is a mirror image of FIG. 6; and,

FIG. 8 is an exploded, top, front perspective view of the two individual cremation urns as shown to be cooperatively engaged in FIG. 1.
